UNITED STATES PATENT OFFICE

FRANK J. LE CLAIR, OF ATTLEBORO, MASSACHUSETTS

DESIGN FOR A FLASK

Application filed June 4, 1931. Serial No. 40,082. Term of patent 3½ years.

To all whom it may concern:

Be it known that I, FRANK J. LE CLAIR, a citizen of the United States, residing at Attleboro, in the county of Bristol, and State of Massachusetts, have invented a new, original, and ornamental Design for a Flask, of which the following is a specification, reference being had to the accompanying drawing, forming part thereof.

The figure is an elevational view of a flask showing my new design.

What I claim is:—

The ornamental design for a flask, substantially as shown.

In testimony whereof I have affixed my signature.

FRANK J. LE CLAIR.
